Primary Examiner — Mark Goodwin(74) *Attorney, Agent, or Firm* — Patterson Thuente Christensen Pedersen P.A.(57) **CLAIM**

I claim the ornamental design for canvas lift bucket with safety cover, as shown and described.

DESCRIPTION

FIG. 1 is a perspective view of a canvas lift bucket with safety cover according to an embodiment of the invention.

FIG. 2 is a perspective view of a canvas lift bucket with safety cover according to an embodiment of the invention with the top partially open.

FIG. 3 is a side elevational view of a canvas lift bucket with safety cover according to an embodiment of the invention.

FIG. 4 is a side elevational view of a canvas lift bucket with safety cover according to an embodiment of the invention that is a quarter of a turn from the depiction of FIG. 3.

FIG. 5 is a side elevational view of a canvas lift bucket with safety cover according to an embodiment of the invention that is opposed to the depiction of FIG. 3.

FIG. 6 is a side elevational view of a canvas lift bucket with safety cover according to an embodiment of the invention that is opposed to the depiction of FIG. 4.

FIG. 7 is a top planform view of a canvas lift bucket with safety cover according to an embodiment of the invention; and,

FIG. 8 is a bottom planform view of a canvas lift bucket with safety cover according to an embodiment of the invention. The broken lines in the drawings represent stitching and are part of the claimed design.
